DESIGN FOR A SHOE

Jacob Abowitz, New York, N. Y.

Application December 2, 1935, Serial No. 59,876

Term of patent $3\frac{1}{2}$ years

To all whom it may concern:

Be it known that I, Jacob Abowitz, a citizen of the United States of America, residing in Borough of Manhattan, city of New York, county of New York, and State of New York, have invented a new, original, and ornamental Design for a Shoe, of which the following is a specification, reference being had to the accompanying drawing, forming part thereof.

The dominant feature of my design resides in the bow which is part of the shoe, same being stitched beneath the surface and passing through slits on both sides of bow.

I claim:

The ornamental design for a shoe, substantially as shown and described.

JACOB ABOWITZ.
